ACOUSTIC-KINETOSCOPE

Philip S. Malickson, Bala, Pa.

Application January 5, 1935, Serial No. 481

1 Claims. (Cl. 88—16.2)

My invention relates to the reproduction of motion-pictures and the synchronous reproduction of sound, and relates particularly to a projecting machine for reproducing motion-pictures and sound from a film having both picture images and sound images thereon.

It is an object of my invention to construct a unitary frame which is sturdy in construction, which is comparatively light in weight, and which is free from vibration during the operation of the film moving mechanism and the sound take-off apparatus.

Another object of my invention is to construct a frame or plate that is simple and light in its structure and which lends itself to inexpensive manufacture in large quantities.

Another object of my invention is to construct a foundation plate wherein the various elements may be placed quickly and accurately upon the plate.

Another object of my invention is to construct a plate for the film driving mechanisms wherein the film driving mechanisms that are located upon each side of the plate may be readily inspected either for assembly, for repairs, or for cleaning.

Another object of my invention is to construct a foundation plate wherein bearings and planar surfaces for supporting and correctly aligning the various mechanisms are integrally formed with the plate.

Another object of my invention is to embody a foundation plate for both the motion-picture mechanism and the sound-on-film take-off devices.

Another object of my invention is to embody a unitary foundation plate which supports the film driving mechanism and houses the photoelectric cell.

Another object of my invention is to arrange the numerous elements upon a frame so that all projector and sound system elements requiring periodical cleaning are easily accessible.

Another object of my invention is to embody a projector which emits a minimum quantity of noise while operating.

Another object of my invention is to provide a projector wherein the film sound track touches no portion of any of the elements, in order that the sound track remains free and clear of scratches; and the film is power driven or pulled every step of the way through the mechanism.

Another object of my invention is to mount the means for shifting the frame as well as the means to tension that portion of the film tra-

versing the stream or beam of light from the condenser lens on a frame that may be easily demounted as a unit either for cleaning for repairs or for replacement and which may be remounted on the frame in correct alignment, 5 even by a person who is not skillful in making mechanical adjustments.

Another object of my invention is to provide a single guideway leading from a supply to a take-up reel so that the film may be directed 10 edgewise through the entire guideway to properly position the film in the machine.

Other objects of my invention are to provide an improved device of the character described of simple and economical construction, that possesses a maximum amount of serviceability and of strength.

With the above and related objects in view, my invention consists in the details of construction and combination of parts, that will be fully 20 described when the description is read in conjunction with the accompanying drawings in which:—

Fig. 1 is a side elevational view of my invention embodied in an acoustic kinetoscope 25 projector.

Fig. 2 is a rear elevational view of the device shown in Fig. 1.

Fig. 3 is a sectional view taken on the line 3—3 of Fig. 1.

Fig. 4 is an enlarged side elevational view partly in section, showing the film pressure shoe.

Fig. 5 is a sectional view taken on the line 5—5 of Fig. 1.

Fig. 6 is a sectional view taken on the line 6—6 of Fig. 1.

Fig. 7 is a fragmentary sectional view showing the cooperative arrangement of the exciter lamp, the lens, and the photoelectric cell.

Fig. 8 is a view taken on the line 8—8 of Fig. 1.

Fig. 9 is a perspective view of the front side of the main supporting frame.

Fig. 10 is an enlarged side elevational view of the upper pull-sprocket and its complementary idler rollers.

Fig. 11 is a sectional view taken on the line 11—11 of Fig. 10.

Fig. 12 is a perspective view of the film guide and supporting bracket.

Fig. 13 is a perspective view of the film pressure shoe.

Fig. 14 is a perspective view of the rear side of the main supporting frame.

Fig. 15 is a perspective view of the train of related gear wheels.

Fig. 16 is a fragmentary sectional view of the oil well.

5 Fig. 17 is a sectional view taken on the line 17-17 of Fig. 5.

Referring in detail to the drawings, in Figs. 1 and 2 is shown a sound-on-film and picture projector within a housing. The housing or 10 casing, generally designated as A, is described in considerable detail in my copending patent application, Serial No. 796,089, filed September 29, 1934.

In my invention I embody the sound-on-film 15 and the motion picture film projectors in one housing and the amplifying apparatus in another housing. However, the present description and disclosure relates only to the motion picture and sound-on-film projector.

20 An integrally formed plate, generally designated as B, is positioned to extend vertically in the chamber formed by the housing A. The plate B, preferably formed of metal in a mold and then machined, is retained in position by 25 means of holding bolts 10 passing through the ceiling of the housing and through a flange 12, which flange is formed integrally with the plate B; holding bolts 14, also, passing through the base of the housing and bottom flanges 15, 16, 17 30 which flanges are formed integrally with the plate B. A shock-absorbing piece of material 18, such as rubber, is disposed between the ceiling and the top of the plate B, and a similar piece 10 is disposed between the bottom of the plate 35 and the upper surface of the plate. Thus, the plate is not only retained in position by the holding means, but the plate is cushioned so that shock or vibration is not transmitted to or from the housing.

40 On one side of the plate is located the mechanism that actuates the sprockets and the intermittent claws which move the film F, and the other side of the plate supports the various sprockets and roller which engage the film, in 45 addition to the photoelectric cell and its cooperative mechanisms.

The plate or frame B upon which the film moving instrumentalities are mounted is primarily a metallic casting comprising an elongated but thin body portion 21; however, 50 strengthening elements, such as ribs 22, radiate from the portion to be strengthened to a bead or reenforced border 23 of the plate.

The frame B of a general trapezium shape has 55 a vertically extending rear edge B1, and a front edge B2 which extends parallel to the rear edge for only a portion of its length. The upper edge B3 of the frame is joined at one end to the upper irregular portion of front edge B2 and 60 the other edge of the edge B3 joins the vertically extending edge B1. The lower edge B4 is joined to the front edge B2 by a slight bend at one end and joins the vertically extending edge B1 at its other edge.

65 Guide rollers 24 are mounted adjacent a slit 26 in the ceiling of the casing A in order to direct film from a supply reel. To enable an amateur operator to readily thread the film upon the instrument, I form a guide line 28 that depicts the path that the film should take 70 through the machine and, also, the proper size of loops that the operator should make at the time the film is placed into position upon the sprockets, film gate, and sound take-off drum, all 75 of which shall be hereinafter further described.

Tracing the passage of the film through the machine, the film is moved first by a driven upper sprocket 30 that is located adjacent the film gate. The sprocket 30 has one set of teeth spaced about its periphery, which mesh with the perforations in the film, and the sprocket is undercut on its curved bounding surface sufficiently so that two ridges are formed that enable the marginal sides of the film to ride thereon. The single set of teeth is used since the 16 10 millimeter sound-on-film is generally made with only one set of perforations. The undercutting reduces the wearing of the picture image or of the sound track of the film in order to extend the life of the film. The driven sprocket 30 is 15 securely mounted upon a rotatable shaft 32. The sprocket shaft is journaled in a bearing 36 that is integrally formed with the plate B. The width of the bearing 36 both on the front and rear sides of the frame B is sufficient to prevent 20 wobbling of the shaft and, also, prevents any undue bending of the shaft. On the rear side of the frame and joining the hub of the bearing 36 are a plurality of strengthening ribs 33. The ribs 33 terminate either at the bead 23 on the 25 frame or at some other portion of the frame that is to be strengthened.

Cooperative to press the film in engagement with the driven sprocket 30 are two idler rollers 40, 41 that are mounted upon one end of a 30 pivoted arm 42, as is shown in Figs. 1, 10, and 11. The purpose of pivoting the arm 42 is to enable the film to be threaded upon the sprocket teeth after the arm 42 is moved downwardly so that the idler rollers 40, 41 are distantly removed instead of in engagement with the driven sprocket 30.

The arm 42 has its other cam end 44 shaped as a hyperbola so that a spring 45 urges a plunger 46 against the hyperbolic surface of the arm, which surface is located to one side of the vertex of the hyperbola, in order to retain the arm in a predetermined position. The hyperbolic cam when engaged by the spring pressed plunger 46 positions the rollers 40, 41 either close 45 to the sprocket, when the film is to be fed, or distantly from the sprocket 30 at the time of threading the film on the machine.

From the sprocket 30, the film passes by a film gate, generally designated as C, which is illustrated in Figs. 4, 5, and 12. A suitable means is provided for positively moving the film in a rapid intermittent motion across the light path so as to momentarily position the picture directly in front of the light aperture in the film gate. The means I use to intermittently move the film is a claw 48 which is actuated by a cam. The claw 48 has one end slotted which slot moves about a fixed shaft, which shaft is retained by a trunnion 49. The trunnion extends horizontally in the front face of the plate 13 and is integrally formed therewith. The trunnion is located adjacent the rear bead B1 and close to the upper portion of the plate cutaway portion.

Because of the relatively high speed at which the film is operated, it has a tendency to continue its motion during the retraction or return movement of the feeding claw. For this reason, I use a pressure shoe which tensions the film 70 so as to stop it abruptly at the end of each feeding stroke of the claw.

If the film is not stopped abruptly at the end of each feeding stroke of the claw, then each frame of pictures on the film will not properly 75

register with the aperture through which the rays of light pass. Any variation in the position of the picture and the light aperture is greatly magnified on the screen and, therefore, 5 it is highly desirable that every picture on the film should be stopped in exactly the same position in the stream of light.

The film gate C is comprised of a light interceptor plate 50, illustrated in Figs. 4, 5, 12, 13 10 and 17, which intercepts the rays of light that are projected forwardly through an aperture in the plate from a projection lamp 138 located in a rear compartment or lamp house 170.

The plate 50 is mounted upon a support or 15 bracket 90 which forms a demountable unit. The rear planar surface of the bracket 90 is adapted to rest against the plane embossment 51, the latter being integrally formed as part of the front face of the frame B. Two small studs 20 52A, 52A, placed adjacent openings 52B, 52B in the embossment 51, align the bracket 90 into a predetermined position by interfitting with openings 53A, 53A on the bracket, so that openings 53B, 53B on the bracket register with the openings 52B, 52B, for the reception of holding bolts or screws. By the above described arrangement 25 a person not skilled in making mechanical adjustments could not incorrectly align the bracket and the instrumentalities carried thereon; after 30 the gate assembly is to be replaced after cleaning or its return from the factory for repairs or in exchange for another unit.

The front wall of the interceptor plate 50 has a vertically disposed recess which recess forms 35 a film guide by virtue of the two vertically extending walls 55, 56 and the wall of the plate 50. A metallic vertically extending aperture mask or film framer 58, see Figs. 12, located within the recess hereinbefore described, has an aperture 60 therein which registers with the aperture in the interceptor 50. However, the aperture 60 in the mask has a smaller area than the interceptor aperture and when properly adjusted shuts off the image outside the border of the 40 frame of the film. The mask is connected to a pivoted lever 64 so that movement of the lever which is readily accessible to the operator, moves the mask or framer upwardly or downwardly in order that the picture on each frame of the film will be shown on the screen. When the free end 45 of the lever 64 is moved upwardly the frame descends, and when the free end of the lever 64 is moved downwardly, the framer ascends.

Located in the plate 50 below the light aperture is a slot 66 for accommodating the prongs 50 of the film feeding claw 48.

The film tensioning device comprises a vertically positioned shoe 70, see Figs. 4, 13 and 17, having an opening 72 therein which opening is adapted to register with the light aperture 60. 60 The longitudinal central portion of the shoe is depressed so that vertically extending marginal sides 73, 74 of the shoe form a pair of base rails which frictionally engage the longitudinal marginal sides of the film F in order to press the film against the interceptor plate 50. The shoe 70 is secured to a vertically extending plate by a pair of horizontally extending studs 77, 78, and embracing the studs are helical springs 79, 80 that urge the shoe 70 toward the interceptor plate for exerting pressure on the marginal portions of the film.

Formed in the shoe 70 is a slot 82 which registers with the slots 66, for receiving the film feeding claw 48.

75 A horizontally extending arm 84, illustrated

in Fig. 13, is integrally formed with a shoe supporting plate 76, and the arm 84 is bent to a right angle; and the right angle portion of the arm, designated as 86, is shaped to move backwardly and forwardly in a recess 88, see Fig. 12, of a support 90 for a projector lens 91. A spring press member 92, shown in Fig. 4, urges the arm 86 in the direction of the film.

A movable projector lens 91 is positioned to one side of the aperture through which the light rays pass so that the optical system may be focused on a reflecting screen which may be placed at a variable distance from the lens.

To enable the film to be easily inserted into the guideway, means are provided for manually shifting the shoe 70 in a horizontal direction. The means for manually shifting the shoe comprises a lever 94 securely fastened to the arm 84. A spring pressed tension shoe release lever 96, illustrated in Figs. 1, 4 and 6, is pivotally mounted upon the frame B so that one end of the lever either fits into a groove 98 on the arm 86, or rests upon the lever. The groove 98 is located so that the arm 86, as viewed in Fig. 4, must be moved to the right before the lever 96 and the groove 98 interfit. That is to say, when the shoe is moved away from the film gate to insert the film in position, the lever 96 will interfit with the groove 98, thus holding the shoe 70 away from the gate. To release the shoe, the operator pushes the free end of the lever 96 so that its end within the groove moves outwardly of the groove, and the spring pressed member 92 then urges the shoe against the film.

The film then passes from the film gate about 35 an idler or impedance roller 100, see Figs. 1 and 8, which has its curved bounding surface depressed so that only the marginal sides of the film engage the roller. A roller 102, carried by a spring pressed lever, which is pivoted to a 40 trunnion or boss 103 integrally formed with the front side of the plate, presses the film against the idler roller 100 and another idler 104 is placed adjacent the roller 100 and directly above a drum 106 that houses a photo-electric cell 107. 45 The idler 104 is carried by a shaft which is screwed into another trunnion or boss 105, the latter being integrally formed with the plate B. The impedance roller 100 revolves on a shaft 100A which is screwed into a trunnion 100B 50 which is integrally formed with the Frame B. A spring 100C surrounds the shaft 100A and has its respective ends engage the roller and the trunnion.

From the spring pressed impedance roller, the 55 film passes about a photo-electric cell drum housing 106 which has a cylindrical wall. The central portion of the outer surface 108 of the housing 106 is depressed so that again only the marginal edges of the film will be contacted. 60 A slit 109 is positioned in the housing so that rays of light from the exciter lamp may pass through the sound objective lens 110, the film sound-track, the slit 109, and impinge upon the photo-electric cell 107 where the intensity of 65 the rays of light, received by the photo-electric cell, is transformed into electrical energy and the electrical energy is carried to an amplification system. The amplification system, however, does not form a part of this invention. 70

The sound objective lens has a stud thereon which is adapted to fit into a cooperative slot adjacent a split on a detachable supporting bracket, generally designated as H. The interfitting stud and slot insures the correct mount- 75

ing of the objective lens in its holder or bracket. A flange 115 on the bracket H is adapted to be fitted against a plane embossment 115A, which is integrally formed with the plate B. A plurality 5 of openings in the flange and in the embossment for the reception of holding bolts or screws permit the proper alignment of the holding bracket H.

The film continues on its journey to a lower 10 driven sprocket 112, which is carried on a shaft 113 that is carried on a bearing 113A. The sprocket is driven at a constant speed, and a single set of suitably spaced teeth on the surface of the sprocket mesh with the single row 15 of perforations on the film. A spring pressed outer roller 114, carried by an arm that is pivotally mounted on a trunnion 114A which is formed with the plate A, likewise engages the lower driven sprocket 112 and the marginal 20 sides of the film rides thereon as a result of the curved bounding surface of the sprocket having its central portion depressed so that the edges of the film are only engaged. The film passes over another idler roller 116, which is 25 mounted on a shaft that is held by a boss 116A prior to entering the film valve guides 118 where it is rolled upon a take-up reel. The boss 116A is integrally formed with the plate B and extends in a horizontal plane on the front of the 30 frame B.

An annular ring 120, located at the approximate center and integrally formed with the plate B, serves to carry a socket 166 upon which the photo-electric cell is mounted as well as a 35 support for the photo-electric cell housing 106, and a plurality of strengthening ribs 22 merge with and extend from the annular ring to the bead 23 of the frame B, which is illustrated in Fig. 14.

40 The entire movable apparatus is driven by a constant speed electric motor 126, which is controlled by a governor. The motor's drive shaft 128 rotates a belt 130 which is connected by means of a pulley 132 with what is termed a 45 primary drive shaft 134, this shaft serves to drive the take-up reel and the driving sprockets, as herein shall be further described. Mounted upon the drive shaft 128 of the motor are a series of fan blades 136 which force a draft of 50 air in and around the source of illumination, which is the electric projector lamp 138. It is necessary to cool the lamp in order to prevent the rapid deterioration of the filament in the lamp.

55 A reflector 139 is adjustably mounted upon a horizontally located circular support, 139A by means of a clamp that is held taut to the support 139A by virtue of a set screw. The reflector may be rotated about the horizontal support 139A with the support as its center. The reflector 139 is also vertically adjustable in height by means of a clamp grasping a vertically extending portion 139B of the circular reflector support.

60 The primary drive shaft 134, see Figs. 3, 6, and 15, suitably supported by a bracket 140 and a bearing 140A which is integrally formed with the frame B, carries two pinion gears 141, 142 as well as a cam or eccentric 144 which moves the 65 film moving claw 48. A knurled starting wheel 134A is suitably attached to the shaft 134 so that it extends on the front side of the frame within easy reach of the operator. The wheel 134A enables the operator to turn all the driven 70 mechanisms during the time the motor is off.

The pinion 142 on the drive shaft 134 is in mesh with the first of a train of intermediate gears 150, 151 and 152, the latter gear meshes with the driven gear 153; and the latter gear rotates the sprocket 30 and the shaft 32. The pulley 5 and the gear train reduces the number of revolutions of the motor, hence, the speed of the sprocket 30 is greatly reduced as compared to the speed of the motor.

80 Mounted upon the same shaft 151B as the intermediate gear 151 is a large gear 155 which is in mesh with another gear 156, the latter is loosely mounted upon the lower driven sprocket shaft 113. The shaft 151B is journaled upon a bearing 151A which is integrally formed with the plate B. As the speed of the lower sprocket 112 is substantially the same as the speed of the upper sprocket, the loop at the gate accommodates itself to the change in speed of the film at the gate aperture. 20

Since the cinema film sound track must pass by the photo-electric cell 107 at a uniform predetermined speed in order to faithfully reproduce sound, the sprocket 112 must revolve at substantially a uniform predetermined speed 25 so that the film will be pulled uniformly pass the photo-electric cell.

A wheel, generally designated as D, possessing a high moment of inertia is securely mounted upon the shaft 113, the latter also carries both 30 the lower take-off film sprocket 112 and the loosely mounted gear 156. The wheel D because of its high moment of inertia and its high momentum while in motion compensates for the speed fluctuations which otherwise would be im- 35 parted to the sprocket 112.

40 A rubber coupling 157, see Fig. 6, which eliminates excessive tension is securely attached to one side of the gear 156 by means of inter-fitting lugs and recesses. From the face of the wheel D extends a plurality of securely fastened studs 151A and the studs extend into suitable located openings in the rubber coupling 157. Thus, movement of the gear 156 revolves the coupling 157, the wheel D and its rigidly attached shaft 113, as well as the sprocket 112. The flat face of the bearing 113A on the rear side of the frame A limits the movement in one direction of the gear 156 along the longitudinal axis of the shaft 113 and the rubber coupling 50 157 limits its movement in the opposite direction.

45 A pulley 158 integrally formed with the gear 155 is mounted upon the same shaft as the intermediate gears 151; the pulley embraces an end of a belt 160 which is connected to a second 55 pulley 162 mounted on a bracket 164 that is fastened to one side of the housing. The second pulley serves to provide the driving means for the take-up reel.

50 Suitably connected to the gear 141 on the primary drive shaft 134 by means of an intermediate gear 165 is a shutter gear 167, see Figs. 2 and 15, that is mounted upon the same shaft 167A that carries a shutter, generally designated 65 as G. The shutter G synchronized with the intermittent claw mechanism 48 interrupts the light beam during the time of the feeding of the film.

70 The barrel type of shutter G comprises a cylindrical member, mounted upon the rotatable shaft 167A that is carried by a bearing 167B which is integrally formed with the plate B, and has two oppositely aligned apertures through which apertures the stream of light may pass. 75

The closed portion of the cylindrical member interrupts the light beam periodically.

The interruptions of light not only prevent blurring of the picture as seen by the spectator by cutting off the projected light while the film is being fed, but the interruptions of light also largely eliminate the visual effect of flickering of the picture on the screen.

For a detailed description of the means for supporting and rotating the take-up reel reference is made to my copending patent application, Serial No. 746,088, filed September 29, 1934. Mounted upon the front wall of the housing A above the bracket is a socket 166, see Fig. 2, for connecting the photo-electric cell to a circuit outside the housing, and below the bracket is a socket 168 for connecting an exciter lamp to an external source of power.

Since the exciter lamp E and its cooperative objective lens 110 must be in alignment with the same aperture 109 in the photo-electric cell housing, I provide a means for adjusting the combined exciter lamp and lens unit both in a horizontal and vertical direction. The base of the unit is supported on a circular shaft 171, shown in Figs. 1 and 7, attached thereto which fits into a circular opening in a horizontally extending trunnion 171A, which is integrally formed with the frame B. A set screw 173 passes through the wall of the lug and engages the shaft 171 in order to hold the shaft in a predetermined position. Hence, if through some mechanical inaccuracy it is necessary to shift the unit vertically or horizontally, the operator merely loosens the set screw, moves the unit up or down or sideways as desired, and then tightens the set screw.

The lamp housing 170 is spaced from the walls of the casing in order to reduce the amount of heating of the casing. It is well known that the intense heat generated by the filament heats the metal so highly that a long period of time must pass before the outside of the housing becomes sufficiently cool so that the apparatus may be handled. I overcome this by spacing the housing from the walls of the casing.

The housing 170 forms a chamber so that the blast of air from the fan blades 136 pass completely about the projection lamp 138 and out through the chimney, cooling the lamp 138 and partially cooling the walls of the housing 170.

On the rear wall of the casing, I supply a socket 172 for connecting the external power circuit to the projector power leads. In the electrical circuit, I insert two switches of the snap-switch type in series; one switch 174 controls both the operation of the motor and the lamp, and the second switch 175 controls the lamp. With such control of the power circuit, it is not possible to accidentally or negligently place the lamp only in the electrical circuit, and so ignite the film, since the heat generated by the lamp is sufficient to ignite or burn the film if it remains stationary for a relatively short period of time before the light aperture 12.

Reviewing the operation of the machine, it will be understood that the film is placed upon the reel supporting bracket and a sufficient length of film is drawn from the supply reel so that the film may be threaded around the various rollers or sprockets, care being taken to establish loops in advance and to the rear of the film gate where the claw is positioned. The end of the film is coiled around the take-

up reel, and the machine is now ready for operation. It is also to be understood that the amplifying circuit and the loud speaker are positioned in their proper places and properly connected electrically in circuit.

Since there are numerous bearings or rubbing surfaces on the machine, it is essential that sufficient lubricant be applied to those rubbing surfaces since it would not be convenient for the amateur operator to lubricate each portion surface that requires lubrication. Therefore, I provide in the top of the casing an oil well 180 that retains the ends of ducts or canals 182, the ducts lead to the various surfaces that require lubrication. The oil well is comprised of a circular cup with the ends of copper ducts therein. A spring pressed ball valve 184 permits the passage of oil to the oil well after the ball is pressed from its valve seat. Therefore, it is only essential for the operator to insert the oil in one reservoir, but in this particular application I use two oil reservoirs or lubrication wells.

The flange 16, formed integrally with the lower edge of the plate B, extends transversely to the plate B and is strengthened by virtue of a web 190 that extends from the upper surface of the flange 16 and merges with the body portion of the plate B.

It is to be observed that with the use of a vertically extending foundation plate or bed all the mechanism mounted upon the front and rear sides are in direct view so that for purposes of testing, cleaning or adjusting the mechanism, no intricate casings need be removed, nor will the person who may be working on the mechanism be hampered by the crowding of the individual elements.

The frame or plate also has various apertures, chambers, bearings, plane bosses, and guide studs arranged to facilitate the assembly of the numerous elements comprising the film-moving and sound-reproducing devices.

Although my invention has been described in considerable detail, such description is intended to be illustrative rather than limiting, since the invention may be variously embodied, and the scope of the invention is to be determined as claimed.

I claim as my invention:

A motion picture and sound-on-film projector including a thin frame, a bead on the border of said frame, a plurality of integrally formed laterally extending flanges on the upper and lower edges of said flange whereby the frame may be fastened, a plurality of bearing surfaces integrally formed in said frame whereby rotatable shafts may be supported, a plurality of thin strengthening ribs extending from the bead to the outside surface of said bearings, said ribs being located only upon one surface of said frame, a plurality of planar surfaces on the surface of said frame which surface is opposite to that on which the strengthening ribs are located, a set of openings and studs on one of said planar surfaces, and a member having a complementary set of studs and openings to interfit with said openings and studs whereby said member may be mounted only in a predetermined position, and an enlarged annular member extending laterally from each side of said thin plate and defining a photoelectric cell chamber.
